R. G. WILLIAMS.

POLE MOUNTING.

APPLICATION FILED FEB. 5, 1921.

1,392,730.

Patented Oct. 4, 1921

UNITED STATES PATENT OFFICE.

ROLLAND G. WILLIAMS, OF BRIDGEPORT, CONNECTICUT.

POLE-MOUNTING.

1,392,730.

Specification of Letters Patent.

Patented Oct. 4, 1921.

Application filed February 5, 1921. Serial No. 442,824.

To all whom it may concern:

Be it known that I, ROLLAND G. WILLIAMS, a citizen of the United States, residing at the city of Bridgeport, in the county of Fairfield and State of Connecticut, have invented certain new and useful Improvements in Pole-Mountings; and I do declare the following to be a full, clear, and exact description of the invention, such 10 as will enable others skilled in the art to which it appertains to make and use the same.

This invention relates to certain new and useful improvements in telegraph and telephone pole mountings, and the primary object thereof is to provide a structure for the mounting and securing of poles of this type without embedding the same in the ground or in a cement or other foundation.

20 The invention further aims to provide a mounting which enables the lower end of the pole to be held above the base or foundation upon which it is supported so as to provide an air space to minimize deterioration of the pole due to the action of collected water or moisture.

Further the invention aims to provide novel supports for the pole which supports are formed with reinforcements, which latter function to also afford increased anchorages where embedded in the concrete base.

Still further and other objects will be later set forth and manifested in the course of the following description.

35 In the drawings:

Figure 1, is a fragmentary side elevation of the invention with the base in section;

Fig. 2 is a similar view of a modified form of the invention;

40 Fig. 3 is a similar view of a modified form of the invention;

Fig. 4 is a top plan view of one of the supports, and

Fig. 5 is a similar view of one of the 45 clamps.

In proceeding in accordance with the present invention, a suitable concrete base or foundation, is employed in which one support 2 of a pair of vertical supports or 50 uprights 2 and 3 is embedded at its lower end. The supports have curved inner faces 4 which conformably engage the pole 5 at diametrically opposite sides of the latter and have central stiffening ribs 6 and 7. 55 In the instance of the support 2 the lower end of the rib 6 is embedded in the concrete

base and thus increases the anchorage of the support therein, while in the instance of the rib 7, the latter merges into a web or foot 8 formed integral with the support 3 so and rests upon the upper face of the base 1. The foot 8 is formed with elongated slots 9 to adjustably receive therein the upper ends of bolts 10 equipped with nuts 11, so as to allow of the adjustment of the support 3 to accommodate poles of varying diameters, following which the nuts are tightened to rigidly clamp the foot 8 down onto the base or foundation 1.

The upper ends of the supports 2 and 3 70 are formed with apertures to receive a cross arm bolt 12 which extends through the pole 5 and which acts to tightly clamp the upper ends of the supports against the opposite sides of the pole, upon tightening of nut 12'. 75

The ribs 6 and 7 are further formed with apertures to receive approximately semi-circular straps or clamps 13 equipped with nuts 14, the clamps engaging about the parts of the pole between the supports and 80 preferably have a diagonal and relatively divergent disposition. Two or more clamps may be used on each side of the pole so that the latter is thus held effectively at all points throughout its circumference, the 85 clamps on one side of the pole being reversely inclined with respect to the clamps on the opposite side of the pole.

In the form of the invention shown in Fig. 2, a permanent structure is afforded, 90 i. e., both supports are fixed and immovable being each firmly embedded in the base.

In the form of the invention illustrated in Fig. 3, both supports are adjustable, so as to increase the range of diameters of 95 poles which can be accommodated.

The pole it will be observed is held with space 15 between its lower end and the upper face of the base 1, consequently water can flow through said space and air is accessible thereto to retain the lower end of the pole dry.

What is claimed is:

1. In a pole mounting, a concrete base, a pair of supports having longitudinal ribs 105 one of which supports has its lower end embedded in the base, the other support having a foot which rests on top of the base and is formed with elongated bolt holes, bolts equipped with nuts embedded in the 110 base and received in the said holes, said supports having curved faces, a pole en-

gaged between said faces and having its lower end spaced above the base, a cross arm bolt extending through the upper ends of the supports and through the pole, and 5 semi-circular clamps between the supports engaged with the pole and having their ends extending through the ribs and secured thereto.

2. In a pole mounting, a base, a pair of 10 vertical supports secured at one end to the base, each support being transversely curved and having a vertical rib extending outwardly from the center of the outer side of the curved part thereof, a pole between the 15 supports, the curved parts of the supports conformably engaging the pole, and integral semi-circular rods engaged with the pole and over the curved parts of the sup-

ports and extending through the ribs and having nuts on their ends abutting the exposed side faces of the ribs to draw the supports against the pole. 20

3. In a pole mounting, a base, a pair of vertical supports secured at one end to the base, each support having a central outwardly extending vertical rib between the sides of the supports and at approximate right angles thereto, a pole between the supports, and integral curved rods engaged with the pole and having their ends freely passed 25 through one side of the ribs and having nuts on the ends of the rods directly engaged with the exposed opposite sides of the ribs to draw the rods against the pole. 30

In testimony whereof I affix my signature. 35
ROLLAND G. WILLIAMS.
